ESCUtCHEON FOR HANDLES AND THE LIKE

George E. Dey, Grand Rapids, Mich., assignor to
W. B. Jarvis Company, Grand Rapids, Mich.,
a corporation of Michigan

Application December 23, 1940, Serial No. 371,271

10 Claims. (Cl. 292—357)

This invention relates to improvements in escutcheons for handles and the like.

The main objects of this invention are:

First, to provide an improved escutcheon unit for door handle and other similar hardware.

Second, to provide an escutcheon or similar unit adapted to greatly facilitate the assembly of a door operating handle on a spindle controlled thereby, the escutcheon or like unit being exceedingly simple and inexpensive of construction and highly attractive in appearance.

Third, to provide a telescoping depressible escutcheon structure which greatly facilitates the assembly of a handle on a door control or other spindle without necessitating a depressible or yieldable door panel.

Objects relating to details and economies of the invention will appear from the description to follow. The invention is defined in the claims.

Preferred embodiments of the invention are illustrated in the accompanying drawing, wherein:

Fig. 1 is a plan view of a handle and escutcheon therefor in accordance with a preferred embodiment of the invention.

Fig. 2 is an enlarged fragmentary view in central section illustrating details of construction and arrangement of the coacting escutcheon and handle parts shown in Fig. 1.

Fig. 3 is a fragmentary view in central section illustrating the escutcheon and handle structure of Fig. 2, with the parts of the escutcheon in collapsed position to permit the insertion or removal of the handle retaining pin.

Fig. 4 is a bottom plan view of the escutcheon unit.

Figs. 5 and 6 are views in central section illustrating escutcheons in accordance with further modified embodiments of the invention.

Fig. 7 is a sectional view of still another modified form or embodiment of my invention.

This invention relates to escutcheon assemblies for handles or other operating hardware of automobiles and the like, and in particular to an assembly of the type described which is very compact and inexpensive in construction, and which enables the ready and quick assembly of the handle or other operating member on a spindle controlled thereby, also the manipulation of the escutcheon to expose a locking pin when it is desired to remove the handle.

Referring to the drawing, in Figs. 1 to 4 I illustrate an escutcheon with the preferred embodiment of my invention. Reference numeral 1 in general indicates the escutcheon and reference numeral 2 a handle associated therewith

and adapted to be connected to a door latch or other member operating spindle 3 of non-circular section by means of a pin 31. This pin is engageable with a transverse hole 4 in the spindle 5 and a coacting transverse hole in the shank 5 of the handle, which is brought into alignment with the spindle hole when the spindle is inserted through an opening 6 in the door panel 7 or other support and into a non-circular opening 8 in the handle shank.

The escutcheon 1 is a telescoping collapsible structure enabling the coacting pin receiving holes of the spindle and handle shank to be exposed to give access for the insertion of the pin in assembling the parts, or in removing the handle relative to the spindle. The escutcheon structure is clearly illustrated in Figs. 2, 3 and 4 and consists of an open dished or cupped circular base stamping 9 having the upturned annular rim 10 and a central opening 11 which is aligned with the panel opening 6 in assembling the escutcheon. Coacting with the base 9 is the dished annular top escutcheon member 12 having the downturned annular flange 13 in external telescoping engagement or association with flange 10. The two telescoped parts receive and house a conical coil compression spring 14, the upper or top escutcheon member 12 having a central opening 15 engageable externally on or receiving the handle shank 5 and provided with the in-turned annular lip 16 or flange defining the shank engaging opening. In the preferred embodiment, this flange is curved outwardly for anchoring engagement with the top coil of spring 14, said coil being slightly smaller in diameter than, or somewhat eccentric of, the outturned lip of said flange and being snapped thereover in assembly. Thus the spring is secured in unitary assembled relation to the top escutcheon member. The bottom escutcheon member 9 has tabs or lugs 17 struck up therefrom in spaced relation to the flange 10 to receive and locate, and, if desired, to lockingly position the bottom coil of the spring, thereby controlling the parts as a unit.

In assembling the handle and escutcheon structure, escutcheon 1 is placed over the spindle 3 in alignment with the panel opening and is then compressed to expose spindle opening 4, whereupon the handle 2 is telescoped on the spindle and a pin 31 inserted in the aligned handle and spindle holes to lock the parts together. The position of the collapsed parts is clearly illustrated in Fig. 3. After this, the escutcheon is released to permit the spring to urge the top

member 12 into its final operative relation to the handle concealing the locking pin. It should be noted that the above described telescoping and collapsible escutcheon assembly does away with the need for relying on a depressible upholstery panel such as has been employed in many heretofore known structures. The parts thereof are simple, inexpensive, and self-contained and greatly facilitate the handle assembly operation.

In Fig. 5 I illustrate a somewhat modified embodiment of my invention wherein a molded plastic composition, colored in any desired manner, is employed for the top annular dished member of the unit, here designated by the reference numeral 18. Elements of that type may be produced in such plastics in a number of attractive color effects or finishes to blend with any interior hardware or decorative color scheme or arrangement. In such a molded construction the upper member is provided with a central annular cylindrically flanged opening for the reception of the handle shank, the upper coil of the spring 19 being preferably made slightly smaller in diameter than the flange 20 of this opening, or distorted to a slightly out-of-round condition to assure a gripping action maintaining the spring and escutcheon top part in desired relation and thereby facilitating their assembly. The lower annular dished half 21 of this embodiment, illustrated as a stamping, receives the enlarged lower coil of the spring and is provided with an indentation 22 for engaging and locking the said coil in place, thereby constituting the escutcheon a unit. Manipulation of the unit in assembling or removing the handle is the same as in the embodiment of Figs. 1 to 4.

In Fig. 6 I illustrate a further embodiment of my invention wherein an ornamental base 23 of molded plastic is employed, this base being provided with a central shouldered opening 24 serving as an abutment for the lower coil of the spring 25. The upper or top escutcheon member 26, that is, the annular flange 27 thereof, is telescopingly received in the enlarged portion of the opening, and the upper coil of the spring is grippingly received by the downwardly and outwardly curved flange 28 defining the central handle shank receiving opening.

In the embodiment shown in Fig. 7 the base member 28 is provided with an inturned flange 29 surrounding the spindle opening thereof, this flange being shaped like the inturned flange 16 of the top member 12. The coils of the spring 30 are of dimensions uniform with the bottom coil engaged with the flange 29, the same as the top coil is engaged with the flange 16.

In all of the foregoing structures, a unitary escutcheon is provided which is exceedingly compact in nature and economical in its parts. Assembly of the same with a handle on a door panel in operative relation to an operating spindle is greatly facilitated by the depressible operation of the escutcheon and many very attractive ornamental effects may be produced suitable for almost any conceivable interior or exterior decorative scheme.

I have illustrated and described my invention in embodiments which are very practical. I have not attempted to illustrate or describe other embodiments or adaptations as it is believed this disclosure will enable those skilled in the art to embody or adapt my improvements as may be desired.

Having thus described my invention, what I

claim as new and desire to secure by Letters Patent, is:

1. An escutcheon unit for automobile door handles and the like having a telescoping spindle and handle shank, comprising a dished base member having an annular upturned flange and an axial aperture for receiving the spindle, an outer dished escutcheon member having an annular flange externally telescopingly engageable with the base member flange and a centrally flanged opening concentric with the base member opening to telescope on the handle, and a coil spring disposed internally of said members and concentrically thereof, one of the end coils thereof being smaller than the other and in lateral gripping engagement with the central flange of the escutcheon member and axially abutting the escutcheon member, and the opposite coil abutting and being clampingly positioned by the base member, said members and spring being secured together as a unit by said gripping engagement and clamping positioning, and the members being relatively collapsible in opposition to said spring to expose a portion of said handle normally covered thereby to view, means locking the handle and spindle together when the spindle and handle shank are in telescoped engagement.

2. An escutcheon unit for automobile door handles and the like, comprising a dished base member having an annular upturned flange and an axial aperture for receiving a handle-operated spindle, an outer dished escutcheon member having an annular flange externally telescopingly engageable with the base member flange, and a centrally flanged opening concentric with the base member opening to telescope on the handle, and a coil spring disposed internally of said members and concentrically thereof, one of the end coils thereof being in lateral gripping engagement with the central flange of the escutcheon member and axially abutting the escutcheon member, and the opposite coil abutting the base member, whereby said escutcheon and base members are secured in unitary relation by said spring, said members being relatively collapsible in opposition to said spring to expose a portion of said handle normally covered thereby to view.

3. An escutcheon unit for automobile door handles and the like, comprising a dished base member having an annular upturned flange and an axial aperture for receiving a handle-operated spindle, an outer dished escutcheon member having an annular flange telescopingly engageable with the base member flange and a centrally flanged opening concentric with the base member opening to telescope on the handle, and a coil spring disposed internally of said members and concentrically thereof, one of the end coils thereof axially abutting the escutcheon member and the opposite coil abutting the base member, said spring having securing engagement with said escutcheon and base members to secure the same together as a unit, said members being relatively collapsible in opposition to said spring to expose a portion of said handle normally covered thereby to view.

4. In combination with a spindle and a handle telescoped thereon and adapted to receive a locking key, an escutcheon unit for said handle associated between the same and a backing panel, comprising a dished base member adjacent the panel and provided with an annular out-turned flange, a top member normally concealing said key and having an annular inturned flange telescopingly engageable with said base member

flange, and a coil spring disposed in said members and in thrust transmitting relation thereto, to urge same for axial abutting engagement with the panel and handle respectively, said members having concentric alined apertures for the reception of the spindle and handle, and means integral therewith for securing said coil spring to said members to constitute the members and spring a unit, said members being relatively collapsible axially to expose said handle for access to the key.

5. In combination with a spindle and a handle telescoped thereon and adapted to receive a locking key, an escutcheon unit for said handle associated between the same and a backing panel, comprising a dished base member adjacent the panel and provided with an annular out-turned flange, a top member normally concealing said key and having an annular inturned flange telescopingly engageable with said base member flange, and a coil spring disposed in said members and in thrust transmitting relation thereto, to urge the same for axial abutting engagement with the panel and handle respectively, said members having concentric alined apertures for the reception of the spindle and handle, and means integral with at least one of said members for securing said coil spring thereto, the spring being grippingly secured to the other member to connect the members in unitary relation, said members being relatively collapsible axially to expose said handle for access to the key.

6. In combination with a spindle and a handle telescoped thereon and adapted to receive a locking key, an escutcheon unit for said handle associated between the same and a backing panel, comprising a dished base member adjacent the panel and provided with an annular out-turned flange, a top member normally concealing said key and having an annular inturned flange telescopingly engageable with said base member flange, and a coil spring disposed in said members and in thrust transmitting relation thereto, to urge the same for axial abutting engagement with the panel and handle respectively, said members having concentric alined apertures for the reception of the spindle and handle and said spring being restrainingly connected at its ends to said respective members to connect the same in unitary relation, said members being relatively collapsible axially to expose said handle for access to the key.

7. A collapsible escutcheon assembly for door

handles, remote control handles and the like comprising facing cupped base and top members having telescoping engagement, the top member being provided with a central opening adapted to receive the shank of a handle and having an inturned curved flange, and a conical coiled spring, the smaller outer coil of which is in clutching engagement with said flange of said top member, the larger inner coil of which is seated within the flange of the cupped base member, said cupped base member having lugs retainingly engaging said inner coil whereby the spring acts to retain the escutcheon members in assembled relation and permits the collapsing thereof.

8. A collapsible escutcheon assembly for door handles, remote control handles and the like comprising a base and top members having telescoping engagement, the top member being provided with a central opening adapted to receive the shank of a handle and having an inturned flange, and a conical coiled spring, the smaller outer coil of which is in retaining engagement with said flange of said top member, the larger inner coil of which is seated within the base member, said cupped base member having retaining means engaging said inner coil whereby the spring acts to retain the escutcheon members in assembled relation.

9. A collapsible escutcheon assembly for door handles, remote control handles and the like comprising a base and top members having telescoping engagement, the top member being provided with a central opening adapted to receive the shank of a handle and having an inturned flange, and a coiled spring, the outer coil of which is in retaining engagement with said flange of said top member, the inner coil of which is seated within the base member, said cupped base member having retaining means engaging said inner coil, whereby said members and spring are secured together in unitary assembled relation.

10. A collapsible escutcheon assembly for handles and the like comprising a base and top members having telescoping engagement, the top member being provided with a central spindle receiving opening, and a coiled spring, the outer coil of which is in retaining engagement with said flange of said outer member, the inner coil of which is retainingly engaged with said base member whereby the spring acts to retain the escutcheon members in assembled relation and permits the collapsing thereof.

GEORGE E. DEY.
